VAPOR GENERATOR

Ervin G. Bailey, Easton, Pa., assignor to The Babcock & Wilcox Company, Newark, N. J., a corporation of New Jersey

Application May 13, 1939, Serial No. 273,398

5 Claims. (Cl. 183—85)

This invention relates to improvements in vapor generators and the invention may be considered as exemplified in water tube steam boiler improvements whereby the safe steaming capacities and the water storage capacities of such boilers, for a given drum capacity, are increased.

Among the objects of the invention are the effective separation of steam and water with a minimum of steam and water separation space; the elimination of priming and decrease of water content in the steam leaving the steam and water drum to a minimum; the decrease of the amount of steam in the water in the steam and water drum to a minimum so that maximum density of water is procured; the increase of the safe steaming capacities of natural circulation steam boilers by minimizing the amount of steam in the down-take elements; the increase in boiler circulation rates; and improvements which will enable a given water tube steam boiler to operate at maximum capacities under conditions of higher and more widely varying water levels.

To accomplish these objects the invention involves the combination of novel steam and water separators in a single steam and water drum and in certain definite relationships to the steam and water spaces of the drum, and the circulators discharging steam and water into the drum. It is to be understood, however, that the invention is not limited to all of the details of this combination.

With reference to the separators, it is an object of the invention to provide for the optimum of steam and water separation with a minimum of flow resistance and minimum of re-entrainment of steam in the water, and water in the steam after the initial separation.

The invention will be described with reference to the embodiments illustrated in the accompanying drawings, and other objects of the invention will appear as the description proceeds.

In the drawings:

Fig. 1 is a vertical section of a steam generating installation which includes an embodiment of the invention.

Fig. 2 is a transverse vertical section of a steam and water drum with the illustrative separator therein;

Fig. 3 is a plan section of a steam and water drum showing the arrangement of a number of the illustrative separators;

Fig. 4 is a vertical longitudinal section of the Fig. 3 drum;

Fig. 5 is a vertical section on the line 5—5 of Fig. 6, illustrating an embodiment in which the separator casing is rifled;

Fig. 6 is a horizontal section on the line 6—6 of Fig. 5;

Fig. 7 is a vertical section (on the line 7—7 of Fig. 8) of an embodiment in which the separator casing is formed with parallel lands or

grooves within the steam and water inlet and is partially rifled throughout the remainder of the separator casing;

Fig. 8 is a horizontal section on the line 8—8 of Fig. 7;

Fig. 9 is a vertical section (taken on the line 9—9 of Fig. 10) of a separator embodiment in which a single groove extends from the steam and water inlet to the outlet for separated water; and

Fig. 10 is a horizontal section on the line 10—10 of Fig. 9.

The invention is well adapted to attain a high degree of steam and water separation in high pressure and high capacity steam generators such as that indicated in Fig. 1 of the drawings.

In this installation it is to be noted that the steam and water separation is accomplished within a single steam and water drum, thus illustrating the ability of the invention to provide effective steam and water separation with a minimum of steam and water drum volume or capacity.

In the Fig. 1 installation the steam and water mixtures are discharged by the circulators 18 at high velocity into the drum 12. These circulators are shown as having their inlet ends connected to a header 14 which receives the steam and water from a plurality of risers. Some of these risers define the walls and other boundaries of the furnace 16 and are subject to the high temperatures thereof. Other risers, such as 18—20, define the walls of gas passes 22 and 24 and are subject to high gas temperatures at those positions.

Steam and water is separated within the drum 12, the steam proceeding through the tubes 130 to the superheater 134 while the separated water proceeds through the downcomers 38 to lower headers 32—35, the latter being otherwise appropriately connected into the boiler circulation as indicated. The steam and water discharged into the drum 12 through the circulators 18 enters a separator inlet chamber 40 which is formed within the drum by the side plate 42, the upper and lower plates 44 and 46, and complementary end plates indicated at 48 and 50 in Figs. 3 and 4 of the drawings. This inlet chamber extends throughout the major portion of the length of the drum and has connected thereto a plurality of rifled steam and water separators 51, the arrangement of these separators being indicated in Figs. 3 and 4 of the drawings and their specific construction being indicated in Fig. 2 and Figs. 5—9, inclusive, of the drawings.

In the illustrative separators a plurality of forces are effective during the operation of the vapor generator. Vapor and liquid mixtures enter the whirl chambers from the inlet chamber 40 with a considerable velocity head. Their

flow is substantially tangential to the whirl chambers and it may also be considered as substantially horizontal. These circumstances result in a swirling film of liquid flowing along the wall of the whirl chamber and the centrifugal force thus produced is effective in separating the vapor and liquid.

As the mixture of liquid and vapor enters the whirl chamber horizontally at a high velocity the tendency is for it to continue its motion in the same horizontal zone, so that the film of liquid tends to flow back upon itself creating a layer of liquid of greater depth. While this tendency is naturally modified by the force of gravity, which imposes a vertically downward component on the horizontal velocity component of the incoming stream, thus resulting in a generally downward direction of the film of liquid on the whirl chamber wall in the form of a spiral, the centrifugal force being greater than gravity is such that in acting upon the layer of liquid, the liquid displaced in the thinning down of the layer flows both upwardly and downwardly of the wall of the whirl chamber from the horizontal zone into which the incoming stream is projected. It is desirable, however, to avoid these conditions. As for example, the liquid displaced upwardly of the whirl chamber wall may impact with the top of the whirl chamber resulting in the splashing of such liquid into the steam space in the center of the chamber, where it might be picked up by the steam and carried to the multiple plate separator, or, if the distance above the horizontal zone, to which reference has been made, to the top of the chamber is adequate to prevent this happening, when the centrifugal force in this liquid is dissipated the action of gravity will be to cause the liquid to flow down the whirl chamber wall and on contact with the high velocity incoming stream will tend to splash with the same possibility of resultant pickup by the steam, which is, of course, undesirable. In order that the forces involved might be utilized most efficiently, and the best results as to steam-free water and water-free steam be obtained, it is necessary that these conditions be avoided, and the film of liquid removed from the incoming zone, and all of it discharged downwardly from the bottom of the whirl chamber just as quickly as possible. The rifled or spirally grooved interior wall of the whirl chamber provided by this invention performs this function, as it utilizes the energy of the incoming stream to augment the effect of the force of gravity, and not only definitely initiate but maintain the downwardly flow of the liquid film toward the restricted outlets at the lower end of the whirl chamber. Such restricted outlets are shown as limited to narrow annular zones defined externally by the rifled wall of the whirl chamber and the base, or pan, 56. They may be separated by short helical vanes such as those indicated at 58 and 60 in Fig. 5. The latter are preferably co-ordinated with the rifling, and when secured to the whirl chamber they serve as supports for the pan, or base, 56. The forces involved in the flow of separated water downwardly through these outlets prevents the establishment of liquid levels in the whirl chamber corresponding to the drum liquid levels and enables the vapor generating installation to effectively operate at drum liquid levels ranging essentially from the top to the bottom of the cylindrical whirl chamber. Such as is indicated by the lines AB and CD of Fig. 5.

Beneath the multiple plate separator 52 for

each whirl chamber the steam outlet member 62, formed in the shape of a hollow frustum of a cone, is secured at its upper circumferential edge to the top of the whirl chamber by brazing or welding as indicated at 64. This member not only prevents the liquid swirling in an annular layer at the upper portion of the whirl chamber from being whipped upward so as to be caught by the plates of the separator 52 but also causes liquid falling from the separator 52 to be deflected toward the center of each whirl chamber.

The modification of the separator indicated in Figs. 7 and 8 of the drawings is similar to that above described in many respects, the main difference residing in the extent of the rifling. In the Fig. 7 modification the whirl chamber is not completely rifled, the rifling being limited to a substantially helical band beginning in the inlet structure 70 and continuing through the outlet for the separated water. This leaves a plain surface portion of the interior surface of the whirl chamber between successive groups of the rifling elements. Such a plain surface portion is indicated at 72, disposed between the elements of the rifling 74 and 76 of an upper group and elements 78 and 80 of a lower group.

The embodiment indicated in Fig. 7 of the drawings has a whirl chamber with rifling so arranged that at the time the liquid in the grooves makes one circuit of the whirl chamber, it is below the entrance port, and there is therefore no building up of a return liquid upon the entering stream. The rifling is thus of benefit in effecting more definite downward flow of the liquid swirling along the wall.

In the embodiment indicated in Figs. 9 and 10 of the drawings the interior of the casing 81 is formed with a single helical groove beginning at the position indicated at 82 which is disposed approximately at the junction of the inlet structure 84 and the casing 81. From that point the groove 86 extends helically to and through the water outlet which is formed by the base 90 and the surface of the casing 81 adjacent the base.

As indicated in Fig. 2 of the drawings the whirl chamber casings are secured to the plate 42 by sleeves 110 fixed to the plate and provided with flanges 112 adapted to fit against complementary flanges 114 secured to the inlet structures 116 which are rigid with the casings 51. The whirl chamber casings 51 are further fixed in position by supports 120-122, the latter of which may be welded to the drum with the member 120 detachably secured thereto.

It is to be appreciated that the removal of steam from the water entering the downcomers of a steam generating unit, such, for example, as illustrated by Fig. 1, becomes increasingly important as steam pressures increase because of the decreasing ratio between the specific weight of water and the specific weight of steam. This ratio varies with increasing pressure as indicated below:

65	Operating pressure, pounds	Ratio
200		115
400		57
600		37
900		23
1400		13
2000		7.3
2500		4.6

This ratio is a measure of the gravity force which separates the steam and water. Steam will be entrapped in the body of water beneath

the drum water level if the steam and the circulating water are discharged into the body of water in the drum below the water level or if the steam and the circulating water impinge downwardly on the water surface. It is evident that the separating force of gravity alone decreases greatly with increased operating pressures so that it becomes increasingly difficult to remove any steam entrapped in the body of water as the operating pressure increases. Any steam so entrapped is carried with the circulating water into the downcomers, and, due to the smaller specific weight of the steam, the circulating head is reduced and hence the circulating system balances out at a lower circulating flow. The present invention causes all of the steam and circulating water to be received within separate whirl chambers within the boiler drum, and, by utilizing centrifugal force which is several hundred percent greater than the force of gravity, the steam and water are completely separated. The steam is discharged vertically upward from the whirl chambers at low velocity and away from and above the surface of the water. The separated water is discharged downwardly from the whirl chambers into the body of water within the drum and below the upper surface of that body of water. In this way the body of water below the surface is practically free from steam, and the steam space above the water surface is practically free from moisture regardless of operating pressure or capacity. Therefore, the water in the downcomer supply being practically free from steam insures that the maximum circulating head is produced and the optimum circulating flow is attained, and at the same time the steam being practically free from moisture insures the supply of clean steam to the superheater and subsequent turbine, and the elimination of the troubles previously encountered in such apparatus due to moisture and solids carryover in the steam.

The attribute of the invention whereby it permits the safe operation of steam generators at higher drum water levels also results in increased water storage capacity for the steam generator and simultaneously increases the operative safety factor resulting from such increased water shortage. These characteristics of the invention also permit noteworthy decreases in the costs of original installations by insuring satisfactory circulating characteristics and good quality steam production with minimum of drum capacity.

While the invention has been described with reference to certain particular embodiments thereof it is not limited to all of their details. On the contrary, it is to be considered as of a scope commensurate with the scope of the subjoined claims.

What is claimed is:

1. In a separator for fluids of different densities, means constituting a whirl chamber, an inlet means so disposed as to promote the whirling movement of fluids within the chamber, the inlet means having its longitudinal axis offset with respect to the longitudinal axis of the whirl chamber and transversely related thereto, the whirl chamber being rifled internally with the

rifling beginning at the inlet and extending beyond the zone of the inlet transversely of the whirl chamber, and means forming outlets for separated fluids of different densities, any element of the whirl chamber rifling having a lead which is at least approximately equal to the width of the inlet axially of the whirl chamber.

2. In a fluid separator, a whirl chamber casing of circular cross-section defining a separating zone, means forming a tangential inlet to said zone, means whereby a fluid stream is discharged through the inlet at high velocity, and different outlets for separated fluids of different densities, the casing being rifled from the inlet toward the

outlet for the separated fluid of higher density, the rifling being such that the lead of any element thereof is at least as great as the width of the inlet axially of the whirl chamber.

3. In a fluid separator, a whirl chamber of circular cross section, means forming a tangential inlet to said chamber, spaced outlets for separated fluids of different densities, means in the zone of the perimeter of the chamber for promoting movement of the fluid at higher density toward the outlet for that fluid, said means consisting of a helical groove extending from the elevation of the inlet to a position below the inlet with a lead which is at least as great as the width of the inlet axially of the whirl chamber.

4. In apparatus for separating fluids of different densities, a whirl chamber of circular cross-section, means forming an inlet tangentially arranged relative to said chamber so that a stream of fluids entering the chamber at high velocity will tend to set up a high velocity circular movement of fluid within the chamber, spaced outlets for separated fluids of different densities, and means limited to the peripheral zone of the chamber and disposed adjacent the inlet for initiating movement of the incoming fluid stream toward the outlet for the separated fluid at higher density, said means consisting of a group of spaced helical grooves in the circumferential wall of said whirl chamber extending from the elevation of the inlet to a position below the inlet and being such that the lead of any groove is at least as great as the width of the inlet axially of the whirl chamber.

5. In a fluid separator including a shell providing a whirl chamber of circular cross-section and extending below a liquid level, inlet means whereby the whirl chamber tangentially receives unseparated mixtures of gas and liquid at high velocities, means forming a gas outlet at one end of the whirl chamber, a liquid outlet disposed toward the opposite ends of the whirl chamber and limited to a zone adjacent the perimeter of the chamber, and helical ribs projecting into the whirl chamber from the shell and extending from a position adjacent the inlet to initiate a helical motion of the liquid toward its outlet and to prevent the second whirl of the liquid from the inlet from remixing impact upon the first whirl, the pitch of the said ribs being at least as great as the dimension of the inlet in the direction parallel to the longitudinal axis of the whirl chamber.

ERVIN G. BAILEY.
